HAIR CURLING DEVICE

Franklin Kemp, Wesleyville, Pa.

Application June 20, 1951, Serial No. 232,621

2 Claims. (Cl. 132—34)

1

This present invention relates to a hair curling device and in particular to one in which the curler is mechanically operated.

The primary object of the present invention is to provide a mechanical curler that will engage a lock of hair in such manner as to retain the hair in a more neatly rolled and curled position than heretofore possible by finger means.

Another important object of the present invention is to provide a mechanical hair curler that will effectively curl a lock of hair in a professional manner and in a quick and convenient procedure.

A further object of the present invention is to provide a mechanical hair curler including novel and improved means for actuating the same and selectively preventing actuation of either end.

A still further object of the present invention is to provide a mechanical curler from which a flat professional curl may be easily removed.

Another aim is to provide a mechanical device with manual speed and tension control for safety.

An even further aim of the present invention is to provide a device of the aforementioned character that is simple and practical in construction, strong and reliable in use, neat and attractive in appearance and otherwise well adapted for purposes for which the same is intended.

Other objects and advantages reside in details of construction and operation as more fully hereinafter described and claimed, reference being had to the accompanying drawings forming part hereof where like numerals refer to like parts throughout.

Figure 1 is a plan view of an embodiment of the invention.

Figure 2 is an end elevational view thereof.

Figure 3 is a sectional view taken along line 3—3 of Figure 1.

Figure 4 is a sectional view taken along line 4—4 of Figure 1.

Figure 5 is a perspective view, somewhat reduced, of the device illustrated in Figures 1 and 4, inclusive, and

Figure 6 is a front elevational view of Figure 2.

Referring more particularly to the drawing, there is shown therein, in Figures 1 and 5, a body 1 of cylindrical shape having at its longitudinal center a base 2a supported by a pair of ears 2. Revolvable mounted at either end of the body 1 is a frustro-conical winding mandrel 3.

Transversely slideable with respect to the base 2a is an arm 5 which extends between the base 2a and the body 1. A guide arm 7 is connected to the arm 5 in parallel relation thereto by

means of a block 9 adjacent one end thereof and a forked member 10 at the other end thereof. A thumb rest 6 is formed integrally with one end of the arm 5 and it will be apparent that the guide arm 7 extends between the ears 2 but outwardly of the base 2a.

The forked member 10 anchors the knotted end 11 of a cord 12 which extends through an opening 12a therebeneath in the arm 5 and thence to a winding drum 15 where its other end is affixed and upon which is partially wound.

It will be seen by reference to Figures 1, 2, 4 and 6 that the body 1 has throughout its length a cylindrical bearing for a revolvable shaft 13. This bearing is cut away, as at its longitudinal center, as indicated at 14, to receive the winding drum 15 and is also cut away adjacent one end thereof, as indicated at 16, to receive therein a torsion spring 17 one end of which is anchored to the body 1 and the other end of which is anchored to the shaft 13 to resist the turning thereof. The mandrels 3 may be secured to the body 1 by any conventional means as, for example, the provision of a circumferential groove at each end of the body for the reception of a radial pin carried by the cylindrical portion of the mandrel which overlies the body. These matters are not shown and are deemed to be merely conventional.

A chamber 18 is provided in each mandrel adjacent the inner end thereof and the peripheral wall of these chambers is provided with ratchet teeth 19, as shown in Figures 3 and 4. The teeth in each case extend in the same direction. Attached to each end of the shaft 13 is a spring clutch member or pawl 20 which is adapted to engage the adjacent ratchet teeth 19. This action prevents rotation of the mandrels in one direction.

To operate the curler: grasp the curler by placing the fingers on the body in a position that allows the arm 5 to pass between them. The thumb being placed on the thumb piece 6, pressing the thumb piece 6 and consequently the arm 5 in a direction towards the body 1 will cause the pawls 20 to engage the ratchet teeth 19 and thus revolve the mandrels 3. The end of a lock of hair engaged with the properly tapered mandrel and the above described operation executed will cause the hair to wind upon the mandrel, the coil of hair being formed in such formation known in the arts as a sculpture curl. The coil of hair is then slipped off the mandrel 3 and fastened at the head by any ordinary means, the mandrel 3 remaining permanently to the device.

By turning the device entirely over it will be seen that hair now placed upon either mandrel will be wound in an opposite direction. It will also be apparent that the longer strands of hair may be wound upon either mandrel and in either desired direction by several strokes of the arm 5 by means of the thumb piece 6, the mandrel winding in but one direction only as above described.

While but one form of the invention has been shown and described herein, it will be readily apparent to those skilled in the art that many minor modifications may be made without departing from the spirit of the invention or the scope of the appended claims.

What is claimed is:

1. A hair curler having a body with a rotatable mandrel at its end connected by a one way clutch to a rotatable shaft within the body, the shaft having on it a torsion spring resisting its rotation, said shaft also having a drum about which is wound one end of a cord the other end of the cord attached to a lever mounted on the body,

depression of the lever causing unwinding of the cord from the drum with resultant rotation of the shaft, the torsion of said spring returning the shaft to original position after each depression and release of the lever, and the one way clutch connection causing a step by step rotation of the mandrel.

2. The hair curler of claim 1 in which the said shaft has on each end a winding mandrel and one way clutch, the clutches at each end operating in the same direction to cause step by step rotation of the said mandrels.

FRANKLIN KEMP.
